UNITED STATES PATENT OFFICE.

THOMAS S. SPEAKMAN, OF PHILADELPHIA, PENNSYLVANIA.

TIDAL MOTOR.

SPECIFICATION forming part of Letters Patent No. 235,105, dated December 7, 1880.

Application filed July 9, 1880. (No model.)

To all whom it may concern:

Be it known that I, THOMAS S. SPEAKMAN, a citizen of the United States, residing at Philadelphia, in the county of Philadelphia and State of Pennsylvania, have invented new and useful Improvements in Tidal Motors, of which the following is a specification, reference being had to the accompanying drawings, wherein—

Figure 1 is a vertical section of my invention. Fig. 2 is an elevation, partly in section, of the same; and Fig. 3 is an elevation of a modification of my invention.

My invention has for its object to provide mechanism whereby the rise and fall of the tide may be utilized to raise water in a stand-pipe or reservoir, said water being designed to be used as a motive power for operating various kinds of machinery—as, for instance, to run the electric machines in light-houses and to supply power for operating all other machinery contained in such places, or it may be used to run saw-mills, or for any other available purpose.

My invention accordingly consists in the provision of a cylinder or tank provided with a piston, upon whose rod is secured a float exterior to said cylinder, the latter having pipe-connections with a reservoir or stand-pipe, and which are provided with suitable induction and ejection valves, whereby the ebb and flow of the tide will reciprocate the piston to force water to said reservoir or stand-pipe, the water being forced or pumped thereto both during the upward and downward movement of the piston.

Referring to the accompanying drawings, A represents a cylinder or other tank, of iron or other metal, supported upon piles or other suitable foundations B B.

C is the cylinder-piston, having a rod, c, projecting through the lower end, a, of said cylinder, and is provided with a float, D, as shown, which is held in position and moves up and down between the platform-posts b b, the latter also serving as guides for said float to prevent the current moving said float out of line to strain the piston-rod.

E E are the induction-pipes, proceeding from the top of said cylinder and running down below the level of the lowest tide-water mark, so that their ends will always be immersed in

water. Said pipes are provided with branch pipes e e, which terminate in the lower end of said cylinder, and are each furnished with a coupling or enlarged chamber, e'. From the latter proceed pipes F F, passing up to the stand-pipe G, which is provided with a valve, g, as shown, at its connection with the cylinder A at g'. If desired, the pipes F F may be provided with valves f f at their terminations in the stand-pipe, so as to prevent any back flow or pressure of water therein from said stand-pipe. Within the couplings e' e' are hinged valves e² e², which have one seat against the lower ends of the pipes F F, as shown in Fig. 1, and another against the edge e³ of said couplings, as shown in Fig. 2. When said valves are seated against the ends of the pipes F F they prevent water flowing into or escaping therefrom, and when seated against the edges e³ they stop the flow of water to the branch pipes e e from the induction-pipes E E.

H is an open-topped case secured to cylinder A, and receives stones or other weight, h, to hold said parts firmly upon the foundation B.

The operation is as follows: As the tide flows in or out the float is caused to rise or fall, and, carrying with it the piston, the water flowing into the cylinder by the suction produced by the movement of said piston is thereby forced or pumped to the stand-pipe or reservoir. If, for example, the piston is ascending, as shown in, Fig. 1, the tide supposed to be coming in, the valve g in the stand-pipe G opens and the valves e² e² in the couplings seat themselves against the lower ends of the pipes F F to close the same and prevent water flowing thereinto from the induction-pipes E E. Said water passes into the branches e e, and thence into cylinder A below its piston to fill the vacuum caused by its partial ascent. As the latter moves upwardly the pressure of the water above it, which flowed into said cylinder during the previous descent of the piston, closes the valves e' in the upper ends of the pipes E E; hence said water finds an exit only through the now open valve g in the stand-pipe. When said piston has reached the limit of its ascent and all the water above it has been forced into the stand-pipe the valve g closes, and the tide now running out, the piston falls or is lowered by the descent of the

float, whereupon the valves e^2 e^2 now seat themselves against the edges e^3 e^3 of couplings e' e' , to open communication between the lower end of the cylinder and pipes F F and to 5 shut off the water-supply to the branches e e from the induction-pipes E E. As the piston descends it forces the water beneath it through branches e e , couplings e' e' , and pipes F F to the stand-pipe G, the valves f f opening under the pressure produced thereby. Meanwhile the valves e^4 e^4 open to allow water from the induction-pipes E E to flow into the cylinder above the piston. As long as the tide rises or falls the water will be raised in the stand-pipe, 10 thereby providing a continuous stream of water to be lifted, to be used as a motor, either by conducting it to any of the well-known forms of water or turbine wheels, or to a hydraulic engine, to operate said devices to run all kinds 15 of machinery used in light-houses, mills, or factories, or it may be used for any other desirable purpose.

In the application of my invention to operate the machinery in light-houses it can advantageously be employed to run the electric machine to generate electricity for the lamps, or turn the machinery which revolve said lamps to produce flashing lights; or it may be used to operate an elevator, or for any other 25 known purpose to save labor in such or other places. Any number of cylinders may be employed, and their pistons will discharge the water into a common stand-pipe or reservoir. If desired, the stand-pipe may terminate in 30 a reservoir, as shown in Fig. 3, which also shows a modification of my invention wherein the cylinder A is placed directly upon the sea or river bottom, with the float above the same.

I I' are the valved induction ports or pipes, 35 one for the upper part of the cylinder and the other for the lower part thereof.

K K' are the eduction-pipes, the former taking the water from the upper part and the latter from the lower part of the cylinder. 40 The pipe K terminates within the coupling e' , having valve e^2 , which operates in this construction as already described. When it

seats itself against end of pipe K it opens communication between pipe K' and stand-pipe L and allows the water below the piston 50 G to flow through stand-pipe L to reservoir M. When seated against end of pipe K' the passage is free between pipe L and pipe K, permitting water above the piston to find its way through pipe L to said reservoir. 55

What I claim as my invention is—

1. A tidal motor consisting of a cylinder or tank having a piston whose rod passes through one of the ends of said cylinder or tank, and to the extremity of which is secured a float, 60 said cylinder or tank having suitable valved induction and eduction pipes, whereby the rise and fall of the tide will operate said piston to draw water into and force it out of said cylinder or tank, substantially as shown 65 and described.

2. In a tidal motor, a cylinder or tank having a piston and attached float, valved induction and eduction pipes, arranged substantially as shown and described, whereby the piston 70 will operate to draw water into and force it out of said cylinder or tank both on the upward and downward movement of the piston, as set forth.

3. In a tidal motor, the combination of a 75 cylinder or tank provided with a piston, to the rod of which is secured a float exterior to said cylinder or tank, a reservoir or stand-pipe, and valved induction and eduction pipes interposed between said cylinder or tank and stand-pipe, 80 substantially as shown and described, and for the purpose set forth.

4. The combination of cylinder A, piston C, float D, and stand-pipe or reservoir G, and interposed valved induction and eduction pipes 85 E F, substantially as shown, and for the purpose set forth.

In testimony that I claim the foregoing I have hereunto set my hand this 6th day of July, 1880.

THOMAS S. SPEAKMAN.
